Garrison Smith & Henry Brown, of Philadelphia, Pa.

Assignors of

G. Abbott & A. Lawrence, of same place.

Letters Patent No. 1073, dated Oct 14- 1858.

The Schedule referred to in these Letters Patent, and making part of the same.

To all whom it may concern:

Be it known that we Garrison Smith & Henry Brown, of Philadelphia in the County of Philadelphia and State of Pennsylvania, have invented or produced a new and original Stove design - designated the "National Range."

and we do hereby declare that the following is a full, clear and exact description of the same; reference being had to the annexed drawing, forming part of this specification, which shows the front and end of the range.

The front plate has at its left hand extremity a raised tablet T, ornamented around its edge as shown at B, and bearing the feed door F, and draft door D. The feed door is raised above the tablet by a molding and bears the ornament in bas-relief made up of entwined foliage, designed, arranged and configured as shown in the drawing.

Dec. 10/13

To the right of the tablet T, the front plate bears the oven doors I. and J. raised above the plate by a molding as shown in the drawing. Each of the panels is ornamented in bas-relief by entwined sweeping foliage, arranged and having the configuration set forth in the drawing.

Above the doors the plate has a cavetto molding, bearing in raised capitals and numerals "Patented 1858".

Below the doors I. and J. is the inscription National Range. Abbott & Lawrence, Philadelphia, in raised capitals.

The ends of the plate are rounded as shown at C.

The end plate of the range bears a raised panel P, ornamented in bas-relief with foliage configured similar to the panels I and J, as shown in the drawing.

The top of the plate has a cavetto molding similar to the front plate.

The full details of the ornaments in bas-relief and moldings are as set forth in the drawing.

We claim as new and of our own production, the ornaments in bas-relief and arrangement of moldings, configurated as shown and described and constituting an ornamented stove design, designated as the "National Range".
